UNITED STATES PATENT OFFICE.

ELSIE SHAVER, OF NEW YORK, N. Y.

DESIGN FOR A DOLL.

54,774.

Specification for Design.

Patented Mar. 23, 1920.

Application filed September 12, 1919. Serial No. 323,408. Term of patent 7 years.

To all whom it may concern:

Be it known that I, ELSIE SHAVER, a citizen of the United States, residing at No. 15 East 38th street, in the city, county, and State of New York, have invented a new, original, and ornamental Design for a Doll, of which the following is a specification, reference being made to the accompanying drawing, forming a part thereof.

The figures are plan views of the front (No. 1) and side (No. 2) of a doll showing my new design.

I claim:

The ornamental design for a doll as shown.

ELsie SHAVER.
